FOREIGN PATENT DOCUMENTS

WO PCT/IL99/00059	A1	9/1999
WO PCT/US03/010311	A2	10/2003

Primary Examiner — David Muller*(74) Attorney, Agent, or Firm* — Marsh Fischmann & Breyfogle LLP(57) **CLAIM**

The ornamental design for a medical cooling pad, as shown and described.

DESCRIPTION

FIG. 1 is a perspective view of a medical cooling pad;
 FIG. 2 is a top view of the medical cooling pad of FIG. 1;
 FIG. 3 is a front elevation view of the medical cooling pad of FIG. 1;
 FIG. 4 is a rear elevation view of the medical cooling pad of FIG. 1;
 FIG. 5 is a right side view of the medical cooling pad of FIG. 1;
 FIG. 6 is a left side view of the medical cooling pad of FIG. 1; and,
 FIG. 7 is a bottom view of the medical cooling pad of FIG. 1.
